UNITED STATES PATENT OFFICE.

CHARLES WARD AND CHARLES E. WARD, OF CHARLESTON, WEST VIRGINIA; SAID CHARLES E. WARD, ADMINISTRATOR OF SAID CHARLES WARD, DECEASED, AS- SIGNOR, AS ADMINISTRATOR AND FOR HIMSELF, TO THE CHARLES WARD EN- GINEERING WORKS, OF CHARLESTON, WEST VIRGINIA, A CORPORATION OF WEST VIRGINIA.

WATER-TUBE BOILER.

1,152,248.

Specification of Letters Patent. Patented Aug. 31, 1915.

Application filed January 12, 1915. Serial No. 1,747.

To all whom it may concern:

Be it known that we, CHARLES WARD and CHARLES E. WARD, citizens of the United States, residing at Charleston, in the county 5 of Kanawha and State of West Virginia, have invented certain new and useful Improvements in Water-Tube Boilers, of which the following is a specification.

This invention relates to watertube steam 10 boilers, and has for its object the production of a steam generator provided with alternate rows of larger tubes and banks of smaller tubes arranged as specified and delineated, whereby it is found in practice that 15 the lower portion of the water in the boiler contained in the lower bank of smaller tubes and in adjacent rows of larger tubes may be caused to circulate locally when the boiler is fired and to attain its full circulatory speed 20 some time before the like circulation is established in the whole body of water, or that contained in the higher bank or banks of smaller tubes. Such prompt and earlier, although fractional circulation with respect 25 to the entire contents of the boiler, effects a decided economy in fuel and is a material aid to quick steaming, particularly in very large boilers of the type to which this invention belongs and in the construction of 30 which it is intended to be applied. Furthermore, the setting up of the full circulatory speed in the water of the lowest bank of smaller tubes acts to impress a like movement upon the remaining water.

Watertube boilers constructed in accordance with our invention are found to get up a desired steam pressure in less time and with less fuel than boilers of similar design but lacking the means for quick local and 40 special circulation set forth in this application.

The particular construction and arrangement of parts comprising this invention are illustrated in the accompanying drawings, 45 of which—

Figure 1 represents a vertical section lengthwise of a watertube boiler constructed in accordance with this invention. Fig. 2 is a section of the upper header on the 50 broken line $x-x$ of Fig. 1.

In the drawings and throughout the description the same letter is employed to refer to the same part.

Considering the drawings, in Fig. 1 the furnace is designated by the letter A. 55 Above the furnace are the lower header B and the upper header b. Connecting the headers and directly exposed to the furnace is a row of larger tubes C. The rows of larger tubes extend entirely across the width 60 of the headers as illustrated in Fig. 2. Above the tubes C is a layer of baffle plates c, and next comes a lower bank of smaller tubes D in any number and extent. Sur- mounting the bank of smaller tubes D is a 65 row of larger tubes E, similar to the tubes C in number and position, as this invention is ordinarily constructed. Over the row of tubes E is a layer of baffle plates e. Inter- mediate baffle plates f and f are usually 70 placed as shown in the bank of smaller tubes D, to divide the flow of the heated gases and to direct portions thereof among the tubes D beneath the baffle plates e and near the upper header b, and among the 75 tubes D just over the baffle plates f and near the header B. Over the baffle plates e is located another bank of smaller tubes G, similar to the smaller tubes D. All the tubes mentioned thus far have both ends 80 connected with the headers. As illustrated, the front header B is the lower, and the tubes slant downwardly from a higher point at the rear in the upper header b, to a lower point at the front of the boiler in the header 85 B. This invention is not limited, however, to the particular direction or inclination of the tubes set forth.

Above the bank of smaller tubes G near the header B is a layer of baffle plates g, 90 and intermediate baffle plates H and h are placed in the bank of tubes G, to divide the current of hot gases and to cause them to seek the end portions of the tubes G beneath the baffle plates g and near the header B, 95 and likewise to spread around the end portions of the tubes G above the plates e and near the header b.

The highest row of larger tubes J is im- mediately under the top of the boiler cas- 100 ing and those tubes are exposed directly and throughout the entire length to the current of hot gases. Each of the larger tubes J has one end connected with the upper header b, and the other end connected with the 105 drum j that is arranged transversely over

and in communication with the front and lower header B.

In the operation of this invention, the direct heat of the furnace A quickly starts an upward flow in the comparatively considerable amount of water in the lower larger tubes C and also in the tubes D of the lower bank of tubes. But, the water in the row of larger tubes E is by no means so suddenly heated throughout, and a down-flow takes place in those tubes. Thus there is established a local and very soon a complete circulation in speed and volume of the water in the lowest larger tubes C, the lower bank of smaller tubes D and the larger tubes E just above the lower bank. The movement is communicated to the remaining water and aids the effect of the heat in starting and bringing up to speed the circulation thereof.

Having now described this invention, and explained the mode of its operation, we claim:—

1. In a watertube steam boiler, the combination with a furnace, of front and rear headers, a drum connected with the upper portions of the headers, banks of tubes of relatively smaller diameter connecting the headers, the said banks of tubes being arranged one bank above another, rows of tubes of larger diameter connecting the said headers, one of the said rows of larger tubes being arranged next above the lowest bank of smaller tubes, and another of the said rows of larger tubes being arranged next below the said lowest bank of smaller tubes and directly exposed to the furnace whereby

when the boiler is fired circulation is established in the said lowest bank of smaller tubes and in the said larger tubes next below and above the said bank as described prior to the circulation in the boiler above the said lowest bank of smaller tubes and the said adjacent larger tubes. 40

2. In a watertube steam boiler, the combination with a furnace, of front and rear headers, banks of tubes of relatively smaller diameter connecting the headers, the said banks of tubes being arranged one bank above another, a drum connected with one of the said headers above the upper bank of smaller tubes, a row of larger tubes connecting the said drum with the other header, rows of tubes of larger diameter connecting the said headers, one of the said rows of larger tubes being arranged next above the lowest bank of smaller tubes, and another of the said rows of larger tubes being arranged next below the said lowest bank of smaller tubes and directly exposed to the furnace whereby when the boiler is fired circulation is established in the said lowest bank of smaller tubes and in the said larger tubes next below and above the said bank as described prior to the full circulation in the 60 boiler above the said lowest bank of smaller tubes and the said adjacent larger tubes. 65

In testimony whereof we affix our signatures in presence of two witnesses.
